By Dwyer & Dwyer

UNITED STATES PATENT OFFICE.

CHARLES E. GAYLORD, OF CHICAGO, ILLINOIS, ASSIGNOR TO AARON K. STILES, OF SAME PLACE.

METALLIC CREST-TILING.

SPECIFICATION forming part of Letters Patent No. 440,104, dated November 4, 1890.

Application filed April 18, 1890. Serial No. 348,479. (No model.)

To all whom it may concern:

Be it known that I, CHARLES E. GAYLORD, a citizen of the United States, residing at Chicago, in the county of Cook and State of Illinois, have invented a new and useful Improvement 5 in Metallic Crest-Tiles, of which the following is a specification.

My invention relates to improvements in crest-tiling which is used particularly upon 10 the ridges of gable, hip, or curb roofs, &c., of buildings for purposes of ornamentation.

As crest-tiling of the class to which my invention relates is intended more especially for use upon the cheaper class of houses, where 15 in each instance a comparatively large quantity must be employed, the aim of improvement is necessarily in the direction of economy of manufacture as well as strength and durability.

20 The object of my invention is to provide crest-tiling of a construction which will afford to it the advantages named in an increased degree over the constructions hitherto commonly in use; and to this end my invention 25 consists in a crest-tile having its upper or ornamental portion and one side of its flaring base formed of a single integral layer or thickness 30 of sheet metal, and having the other side of its base of a separate sheet of metal, either part being provided at the joint with a shoulder 35 to protect the joint from rain.

My invention further consists in a crest-tile 40 having its upper or ornamental portion and one side of its flaring base formed of a single integral layer or thickness of sheet metal and provided at the junction of the upper and 45 base portions with a recess.

In the drawings, Figure 1 is a view in end elevation of another form of the tiling; Figs. 2 and 3, broken perspective views of the sections of the tiling shown in Fig. 3, and Fig. 4, a sectional view of still another form of tiling.

In the construction shown in Figs. 1, 2, and 3 one of the diverging sides of the base B is 45 integral with the upper portion A, the sheet from which the parts are formed being bent, as shown in Figs. 1 and 2, to produce a bead affording a recess s. The other side of the base comprises a separate sheet beaded at the

top, as shown in Fig. 3, to slide readily into 50 the recess s, as indicated in Fig. 1, and be thus securely held in place.

In the construction shown in Fig. 4 one side of the base B is integral with the upper portion A, the sheet from which these parts are 55 formed being bent in the manner shown to afford a recess s for the upper edge of the separate part which affords the other side of the base, the parts being riveted together, as indicated at x.

60 It has been usual hitherto to construct metallic crest-tiling of an integral sheet of thin galvanized iron doubled longitudinally at the center to afford the upper portion, which thus comprises two layers of the metal, which are 65 fastened together by rivets, and the base portion formed by spreading the layers apart to cause them to diverge at suitable angles. The upper portion is then cut or punched to give 70 to it a pleasing design. Crest-tiling thus constructed when in use permits water raining upon it to lodge between the layers affording the upper portion, thus causing the metal to rust in a comparatively short time. It also permits the water to lodge between the tiling 75 and ridge-board of the roof, thus tending to rot the latter.

My improved crest-tiling, having its upper portion of one thickness of metal, is free from 80 this objection, and is consequently more durable. Moreover, the pattern of its ornamentation may be such, as shown in Fig. 2, as to permit the adjacent upper edges of two tiles to be stamped out of a sheet by a single operation and without waste of material.

85 What I claim as new, and desire to secure by Letters Patent, is—

1. An ornamental crest-tile for the ridges of roofs, substantially as described, having its upper or ornamental portion A and one side 90 of its flaring base B formed of a single integral layer or thickness of sheet metal, and having the other side of its base of a separate sheet of metal secured at one edge at the junction of the upper and base portions of the 95 other part, and a shoulder provided in either part at the joint to protect the joint from rain, substantially as set forth.

2. An ornamental crest-tile for the ridges of roofs, substantially as described, having its upper or ornamental portion A and one side of its flaring base B formed of a single integral layer or thickness of sheet metal, provided at the junction of the upper and base portions with a recess s, and having the other

side of its base of a separate sheet of metal secured at one edge in the recess s, substantially as set forth.

CHARLES E. GAYLORD.

In presence of—

J. W. DYCENFORTH,
M. J. FROST.
